UNITED STATES PATENT OFFICE.

NORMAN MARSHALL, OF NEWTON, MASSACHUSETTS, ASSIGNOR TO THE MARSHALL-SANDERS COMPANY, OF BOSTON, MASSACHUSETTS.

ELECTRIC SWITCH.

SPECIFICATION forming part of Letters Patent No. 644,745, dated March 6, 1900.

Application filed April 25, 1899, Serial No. 714,465. (No model.)

To all whom it may concern:

Be it known that I, NORMAN MARSHALL, a citizen of the United States, residing at Newton, county of Middlesex, State of Massachusetts, have invented a new and useful Improvement in Electric Snap-Switches, of which the following is a specification.

My invention relates to improvements in the actuating mechanism whereby the switch is made durable and can be constructed cheaply and to insulating the contact-carrying parts from the actuating mechanism and the method of forming said insulation, thus reducing the liability to grounding and of the operators coming in contact with the circuit. I attain these objects by the mechanism illustrated in the accompanying drawings.

Figures 1 to 9, inclusive, relate to that form of my invention adapted to single-circuit switches. Figs. 10 to 19 show that form of my invention adapted to control a plurality of circuits.

Similar letters refer to similar parts throughout the several views.

Fig. 1 represents a general plan view of the switch with the cover removed. Fig. 2 is an elevation of the same. Fig. 3 shows an inverted plan of the switch mechanism proper removed from the base and stationary contacts in which the mechanism is in its locked position. Fig. 4 is a plan of same with the catch just escaping from the locked position. Fig. 5 is the same position of the mechanism as Fig. 3 with the stop-ratchet removed. Fig. 6 is the same device in the same position as Fig. 4 with the stop-ratchet removed. Fig. 7 is a section showing the different elements of the mechanism. Figs. 8 and 9 are details showing the arrangement for insulating the current-carrying plate from the switch mechanism in the single-pole switch. Fig. 10 is a plan view of that form of my invention adapted for the use of a plurality of circuits, showing the insulating-base P with four binding-posts and their corresponding stationary contacts R R' R² R³, also the operating-handle T. Fig. 11 is an elevation of the same switch, showing, further, the moving contact-plates B B'. Fig. 12 shows an inverted view of the

switch mechanism adapted to this style of switch in its locked position. Fig. 13 shows a similar view of the same mechanism in the position in which the catch is just escaping from the stop n' of the stop-plate. Fig. 14 is a view similar to Fig. 13 with the stop-plate removed. Fig. 15 is a section of the operating parts and the spindle. Figs. 16 and 17 relate particularly to the method of making the insulating-block or separator which supports the connecting-plates B B' B² B³. Fig. 18 is a detail view of this supporting-insulator with the parts immediately attached to it. Fig. 19 is an elevation of the mechanism with the stationary contacts, base, and handle removed.

Referring to Figs. 1 and 2, P represents an insulating-base, of porcelain or other suitable material, on which are mounted two binding-posts Q Q', supporting brush contact-plates R R', the whole being properly secured to the porcelain base. The wires being connected to the binding-posts Q Q', current enters at these points and traverses the moving contact-plate B B', which is insulated, as shown by detail Figs. 8 and 9, from the cam catch-plate I, to which it is attached.

The spring S is attached to the spindle F at its upper end, being wound spirally about said spindle. Its end is extended out to engage the upturned portion of the cam catch-plate I, as shown in Fig. 2. Attached to spindle F is a crank-plate K, in the extremity of which is a stud J, which extends through the cam-slot G G' in the cam catch-plate I. Next to the cam catch-plate is the stop-plate N, which is fastened to the porcelain base and has teeth or faces n n n n. The spindle F extends through a slot in the cam catch-plate I and through a round hole in the stop-plate N and is held by a nut or other suitable device from moving in the direction of its axis.

Referring to that form of my invention adapted to a switch with a plurality of circuits, Fig. 10, the wires are attached to the contact-posts in the usual manner, the current of one circuit passing from R through the connecting-plate B B' to the binding-post R', the current of the other circuit passing

from the contact-post R^2 to R^3 through the connecting-plate $B^2 B^3$. $B B'$ being on a different plane from $B^2 B^3$, the rotation of the moving contact-plates one-quarter turn 5 throws them both out of contact with the connections $R R'$ and $R^2 R^3$.

Referring to the view shown in Fig. 12, N is the stop-plate, rigidly attached to the porcelain, having faces $n' n^2 n^3 n^4$. Next to this 10 ratchet stop-plate is the cam catch-plate I , having the catch L extending down into the plane of the stop-plate N and having the slot O to allow the passage of the spindle, and cam-slot $G G'$, into which plays the stud J . 15 K is the crank-plate, carrying the crank-stud J . The cam catch-plate is held from all movement except a lateral one in a direction parallel to the face of the stop-plate, by which it is engaged by the carrier-plate Z , to which 20 is attached the insulating-carrier M , which supports the moving contacts.

The operation of the device is as follows: Referring to Figs. 2, 3, 11, and 12, the catch L of the cam catch-plate I will be seen to be 25 in engagement with the face n' of the stop-plate, (being forced inwardly by the action of the spring and crank-plate,) so that the mechanism is locked from turning in either direction. When, however, the spindle F , 30 carrying the crank-plate K , is rotated by the handle T in the direction of the arrow, as shown in Figs. 3 and 12, the stud J bears against the inner surface of the cam-slot $G G'$ and forces the catch L outward. This 35 cam-slot is so arranged that the distance from the center of the spindle, Figs. 3 and 12, to the end G' of the cam-slot is shorter than the distance from the center of the spindle to the end G by a little over the depth of 40 the faces on the stop-plate N , so that when the crank-stud J by the rotation of the handle arrives at the position G , as shown in Figs. 4 and 13, the catch L of the catch-plate will have been forced off of the face n of the 45 stop-plate. The spring at the same time having been coiled up by the turning of the handle will exert pressure against the cam catch-plate I , causing it to rotate in the direction of the arrow in Figs. 3 and 12, carrying 50 the insulated moving contact plate or plates out of engagement with the stationary contacts, breaking the circuit. The spindle and attached crank-plate and stud J having remained approximately stationary during 55 the very short period of time required by the cam catch-plate to move around, the stud J will have retraced its path in the cam-slot $G G'$ and will have drawn the catch of the cam catch-plate I inwardly to its first position, as 60 shown in Figs. 3 and 12, so that it engages the succeeding face n^2 of the stop-plate. If the handle is further rotated, the operation is repeated, the circuit being made and broken at each alternate quarter-turn of the handle. 65 Referring to Figs. 8 and 9, $B B'$ is the mov-

ing contact-plate, through which are pierced suitable holes, in which insulating-bushings $A A'$ are inserted. Eyelets $H H'$ are passed through these insulating-bushings and through the hole in the catch-plate I , the edges being turned over to secure them in position. This novel construction in single-pole switches is cheap and effectively insulates all parts of the switch mechanism. 70

Referring to Fig. 16, M is a plain disk of 75 fibrous heat-resisting insulating material, commonly known as "laminar" or "indurated" fiber. This is formed into the shape shown in Fig. 17 by the use of steel dies which pierce through the opening, as shown at Y , and carry 80 down the surface W to allow a proper opening for the moving contact-plates $B B' B^2 B^3$. The moving contact-plates $B B' B^2 B^3$ are held in position by insulating-washers $m' m^2$ and a brass disk C , which is connected by rivets 85 with the carrier-plate Z . This method of completely inclosing the moving contacts except the portion which enters the brushes of the stationary contacts is novel and increases the carrying capacity of the switch by a considerable amount for the reason that the arc cannot follow along the edge of the moving contact, as in the usual construction of such devices. This valuable construction is easily and cheaply effected by the employment of 90 my discovery of the property of laminar fiber, which permits of its being molded with considerable square sharp-edged depressions by confining steel dies under great pressure. 95

While the stop-plate is shown in the drawings with four notches or teeth, it may be made with two or more teeth, the cam-slot being arranged to correspond with the required turn of the operating-handle, which should always move that portion of a complete 100 circumference corresponding with the number of teeth or faces on the stop-plate. The stop-plate may also be arranged in the same plane as the cam catch-plate, with teeth projecting inwardly, with a corresponding nose 105 on the opposite end of the cam catch-plate, which would then move inwardly to release, or the stop-plate may be formed with ears extending up into the plane of the inwardly-moving cam catch-plate. 110

The crank-plate and stud may be formed in various ways and shapes, as from one piece of metal with a lip turned up in place of the studs shown in the drawings. 115

Having indicated certain changes from the 120 form shown in the drawings, others may readily suggest themselves which still embody the essential elements of my invention.

I claim as my invention—

In an electric snap-switch, the combination 125 with an insulating-base and ratchet-plate attached to said base and having teeth, of a handle, a spindle extending from the handle, a crank-plate K , rigidly attached to the spindle, a stud J on said plate, a cam catch-plate I 130

having a slot G, G' through which the stud J extends, a catch L formed on the cam catch-plate I and extending downward into the plane of the ratchet-plate, a spring wound about 5 and having one end attached to the spindle and its other end connected to move the cam catch-plate, and a moving contact-bar insu-

lated from but attached to the cam catch-plate, substantially as described.

NORMAN MARSHALL.
